TOWER OR MAST

Harold Cohen, Elizabeth, N. J.

Application May 29, 1943, Serial No. 489,027

2 Claims. (Cl. 189—26)

This invention relates to a field unit which may be used advantageously as a tower or mast for supporting a radio antenna or aerial and for other purposes.

An object of the invention is the provision of a tower or mast which is extensible and retractable in such manner that it may be readily set up for use and also be collapsed.

A further object is the provision of a unit of the indicated character which when collapsed may be transported from place to place, requiring but little space in transit.

A further object is the provision of a portable unit consisting of a telescopic tower or mast and means for extending and collapsing the same.

A further object is the provision in a tower or mast of telescopic sections and improved means for retaining said sections extended and to facilitate the telescopic movement of the sections.

Other objects of the invention as well as the combination, construction and operation of the parts will be apparent from the following description and the accompanying drawings, in which—

Fig. 1 is a view in elevation of a field unit embodying the features of the invention.

Fig. 2 is an enlarged view in elevation of the unit and showing the tower or mast lowered or collapsed.

Fig. 3 is a sectional view taken on the line 3—3 of Fig. 2.

Fig. 4 is an enlarged fragmentary side view showing certain features.

Fig. 5 is a sectional view taken on the line 5—5 of Fig. 4.

Fig. 6 is an enlarged fragmentary vertical section illustrating the manner in which sections of the tower or mast are raised and further how they are retained in the extended relation.

Fig. 7 is a fragmentary side view showing certain features.

Fig. 8 is a sectional view taken on the line 8—8 of Fig. 7.

The tower or mast of the unit is composed of relatively extensible and retractable sections 10 with a base section 11. These sections are tubular and round in cross-section in the present instance. The sections are telescopically related so as to slide one within the other starting with the uppermost until they are nested or retracted as shown in Fig. 2. The sections are of progressively increased length so that one projects beyond the next when the sections are retracted, thus leaving an upper projecting portion for each section except the base section 11 which requires

none. When the sections 10 are in the retracted relation, the tower or mast is then retracted or collapsed. The sections 10 may be extended or raised one at a time and when the sections 10 are retained in the extended relation, by means hereinafter described, the tower or mast is then extended for use as shown in Fig. 1.

In order to facilitate the telescopic or sliding movement of the sections 10 and to give rigidity and stability to the tower or mast when the sections are extended, each of the sections 10 on the outside of the lower end thereof has two spaced series of well rounded protuberances or projections 12. Any suitable number of the protuberances may be provided in each series, there being four in the present instance spaced equi-distantly.

In order to retain the sections 10 in the extended relation and to enable them to be retracted there is provided identical means for adjoining sections which are contiguous to each other or fit one within the other. For this purpose said means consists of two sets of detachable cross-bars 13. The cross-bars of each set extend transversely through the sections 10 parallel to each other, said sections being provided with slots to receive them. The cross-bars of one set are disposed at a right angle to those in the other set, and further, one cross-bar of one set intervenes with those of the other set, as shown most clearly in Figs. 4 to 8. Wedge shape keys 14 extend through the projecting ends of the cross-bars of each set, said cross-bars having slots to receive them. The keys 14 bear against the side of the related outer section and thus firmly hold the parts assembled. The keys 14 as applied to the cross-bars 13 serve advantageously for guying the tower or mast when extended. As shown in Fig. 1, guy lines 15 are with the keys 14 respectively, there being a hole 16 in each key to receive the upper end of the line. The guy lines branch outwardly and downwardly in four radial groups due to the disposition of the keys 14. The lower ends of the lines of each group are clamped and anchored in the ground by a single anchor 17 to which the lines are connected.

It is to be understood the sections 10 are joined or coupled one to another in the raising operation in which the uppermost section is first raised or lifted from its retracted position after which the cross-bars and keys required are applied, and this procedure is followed in connection with the other sections to bring about the erection of the tower or mast. In lowering or retracting the tower or mast the reverse operations are carried out starting with the lowermost section 10.

In order to raise and lower the sections 10 for the stated purposes, mechanism as follows or its equivalent is provided. Extensible and retractable posts 18 are fixed upright on a base 19. The mast section 11 is also fixed upright on said base 19. The posts 18 are braced to the section 11 in any suitable manner. Pulleys 20 are supported on a bracket 21 on the section 11, and pulleys 23 are mounted on each of the posts 18. Grapples 24 are connected with rings 25 and a cable 26 has one end thereof connected with each of said rings. Each cable 26 is trained over a set of the pulleys, namely, two pulleys 23 and one of the pulleys 20. The grapples 24 cooperate with hook-like members or lugs 27 at diametrically opposite sides of each of the upper projecting end of each section 10. The grapples 24 are engaged with the lugs 27 and a pulling force is exerted on the cables 26 by any suitable means to raise or lift the sections one at a time so that they may be joined or coupled in order to put them in extended relation and thus extend the tower or mast. The sections 10 are raised step-by-step and lowered likewise starting with the lowermost section 10. The grapples 24 may be readily engaged with the lugs 27, disengaged therefrom and reengaged therewith in the raising and lowering operation. A rope or cable 28 is attached to the grapples 24 for lowering the same so that after one section is raised, the grapples may be engaged with the next section without requiring an operator to climb. The guy lines 15 may be connected with the keys 14 of the uppermost sets and the lines 15 are carried up as the tower or mast is extended to the limit. The lines are then anchored.

When the unit is collapsed it may be transported from place to place in an auto, truck or the like. Also, the base 19 may have traction

means to render the unit readily portable. The unit may be attached to a trailer so as to be swung into and out of a vertical position and while in the latter position extended and retracted. The unit might also be attached for use to the rear of a truck.

It will be appreciated that the unit is serviceable to military forces, such as the Signal Corps and other mobile branches of the Army and Navy requiring expeditious installation and removal of equipment.

I claim:

1. The combination of a tower or mast composed of telescopically related sections, each of said sections having means to be grappled, with mechanism mounted on the lowermost section of the tower or mast which cooperates with said first means to extend the tower or mast by raising one of said sections at a time, and detachable means to retain the sections in extended relation, said mechanism including a grapple engageable with said first means.

2. A tower or mast composed or relatively extensible and retractable slidably associated sections, said sections starting with the base section being of progressively increased length so that one projects beyond the next when the sections are retracted, power mechanism adapted to exert an upward pulling force, said mechanism comprising extensible and retractable posts, grapples, and guided cables connected with said grapples; means disposed on the projecting portions of the sections respectively adapted to be engaged by said grapples to move said sections one at a time to an extended relation in response to the operation of said power mechanism, and detachable means to retain the sections in the extended relation.

HAROLD COHEN.
